SPRING DECK FOR FURNITURE

William F. Richardson, Carthage, Mo., assignor to Flex-O-Lators, Inc., Carthage, Mo., a corporation of Missouri

Filed July 16, 1958, Ser. No. 748,920
8 Claims. (Cl. 155—179)

This invention relates to new and useful improvements in furniture, and has particular reference to the spring assemblies or bases in cushion type furniture, commonly known as "spring decks."

The principal object of the present invention is the provision of a spring deck which has the form essentially of a flat mesh made of spring wire, and is therefore of extremely low cost as compared to common types of spring decks now in use, but which nevertheless possesses characteristics and advantages presently available only in much more expensive spring assemblies. For example, most flat mesh spring decks have an uncomfortable "hammock" effect whereby the sleeper (in the case of a bed) lies in a "trough" formed by the deck, due to the fact that the mesh itself is inelastic in its own plane and yields only since it is supported by springs around its edges. The present invention overcomes this defect by means of a mesh which is specially constructed so as to be elastically yieldable in all directions in its own plane. In this manner substantially only the portion of the deck to which a load is actually applied will be deflected. This localization of the deflection accomplishes much the same effect as individual coil suspension in inner spring mattresses, and is generally accepted as one of the best known means of obtaining maximum spring comfort. This localization of deflection is further enhanced by a special formation of the mesh which provides minimum transfer of deflection from one portion of the deck area to another.

This object is accomplished by the provision of a mesh comprising a series of generally parallel resilient wires stretched across a frame, each wire being formed to present a series of loops, each of said loops being interengaged with the corresponding loops of the next adjacent wires. Each row of interengaged loops, extending transversely to the general run of the wires, constitutes a series of engaged links so interlocked with each other that they are not freely pivotal, but form a resilient arch, and so arranged that downward deflection of the arch can be accomplished only by flexing the affected links out of planar form into an upwardly convex shape. The links are also slidably relative to each other so as to prevent buckling or "reversal" of the arch when said arch is deflected.

Other objects are simplicity and economy of structure, efficiency and dependability of operation, adaptability for convenient and compact storage and shipping, and adaptability for use in applications other than in furniture, wherever a resilient spring deck or wall may be desired.

With these objects in view, as well as other objects which will appear in the course of the specification, reference will be had to the drawing, wherein:

FIG. 1 is a top plan view of a spring deck embodying the present invention, and

FIG. 2 is a sectional view taken on line II—II of FIG. 1.

Like reference numerals apply to similar parts throughout the drawing, and the numeral 2 applies generally to a frame which may by way of illustration only be designated a furniture seat frame. As shown, it is open and rectangular, comprising parallel side rails 4 and 6, and parallel side rails 8 and 10 disposed at right angles to rails 4 and 6, all of said rails being rigidly joined together in a unitary structure. Extending across said frame are a series of generally parallel, uniformly spaced wires each designated generally by the numeral 12. Said wires are

2

formed of spring stock, and each is formed to present a series of loops 14 which are spaced regularly across the frame and which all lie substantially in the plane of the mesh. Each of the loops is closed, that is, the portions of the wire at the base of each loop are disposed in intersecting relation and extend in opposite directions from said loop. The portions of the wire intermediate the loops may be designated as connecting portions 16. The end loops of each wire are affixed respectively to rails 4 and 6 of frame 2 by any suitable fasteners such as staples 18. Each of the loops 14 of the wire adjacent rail 8 of the frame is affixed thereto by a staple 20, and each of the connecting portions 16 of the wire adjacent rail 10 of the frame is affixed thereto by a staple 22.

It will be seen that each loop 14 of each wire is inserted downwardly through the corresponding loop of the next adjacent wire, so that the former loop itself is disposed beneath the latter loop, and the connecting portions 16 directly adjacent the former loop are disposed above the latter loop, as clearly shown in the drawing. Before the mesh is attached to the frame, it may be rolled very compactly for convenient storage and shipping, thus eliminating much of the expense and excessive space requirements of ordinary spring assemblies. When the mesh is stretched out for application to the frame, it will be seen that the mode of interengagement of the loops prevents the mesh from assuming a planar form and causes it to assume an upwardly convex arch configuration as shown in FIG. 2, the arch extending in a direction transverse to the general run of wires 12.

Each row of interengaged loops 14, extending transversely to the general run of the wires, may be considered as a series of links, each link constituting a loop 14 and the immediately adjacent portions of the connecting portions 16 of the wire forming said loop. Each link is thus supported from beneath at its respective extreme ends by the adjoining links, and said adjoining links also extend inwardly from the extreme ends of the first link, and exert downward pressure on said first link at points spaced inwardly from its ends. In other words, each link is supported from beneath at its ends, and supports a downward pressure at points spaced inwardly from its ends. When the mesh is tensioned for application to the frame, each loop is flexed from its normal substantially planar form to an upwardly concave configuration as clearly shown in FIG. 2. The degree to which the loops are flexed in applying the mesh to the frame represents a "pre-tensioning" of the spring deck, and other factors being equal, will determine the degree of softness or yieldability of the spring deck. Other factors affecting the yieldability characteristics of the deck are of course the gauge and stiffness of the wire used, the tension in the individual wires, and the size and spacing of loops 14. It will be understood that in most applications the deck will be covered by suitable layers of padding and upholstery.

Downward pressure on the deck, as encountered in ordinary usage, merely causes an increase in the upwardly concave curvature of the loops 14. The application and removal of loads to the deck will cause changes in the effective length of the arch between frame rails 8 and 10, particularly a shortening thereof as the arch is compressed or flattened under load. This would cause a buckling, humping, or even possibly a downward reversal of the arch, if it were not for the fact that the links formed by loops 14 are slidably relative to each other in the direction of the arch. This sliding relation of the links permits the length of the arch to be varied by changing the degree of overlap between adjacent links, and thereby prevents any buckling or humping of the arch.

Another important feature is that since the mesh is resiliently yieldable in its own plane in all directions, the

deflection thereof when a load is applied to a restricted portion thereof will be restricted to the immediate area of the load application. This localization of deflection is in accord with accepted standards for greatest comfort, and is not obtainable in the usual flat mesh deck which is not itself resiliently yieldable in its own plane, but is resiliently supported around its edges. This localization of deflection is further enhanced by the "closed" configuration of loops 14. A load on any portion of the deck exerts opposite tension on the connecting portions 16 of the wire adjacent each of the affected loops, tending to contract said loop to a smaller size. Since the loop may be so contracted to a considerable degree without appreciably displacing the loops in adjoining wires to which it is connected, and since the contraction increases the length of connection portions 16 extending to adjacent loops in the same wire in order that any contraction of the latter loops is greatly reduced, it will be apparent that the deck deflection even in areas closely adjacent a zone of load application will be greatly reduced, and will decrease very rapidly as the distance from the load zone increases.

While I have shown and described a specific embodiment of my invention, it will be readily apparent that many minor changes of structure and operation could be made without departing from the spirit of the invention as defined by the scope of the appended claims.

What I claim as new and desire to protect by Letters Patent is:

1. A spring deck for furniture comprising a frame, a plurality of arches extending in generally parallel relation across said frame and secured at their respective ends to said frame, each of said arches comprising a series of spring links each extending longitudinally of said arch and being resiliently flexible in a direction transverse to said arch, the said links comprising each arch being interconnected with successive links overlapping each other in a direction longitudinal to said arch, the respective extreme end portions of each link being disposed above and bearing downwardly against the next adjacent link in spaced relation from the end thereof.

2. A spring deck as recited in claim 1 wherein the spring links in each of said arches are slideable relative to each other longitudinally of said arch.

3. A spring deck as recited in claim 1 wherein each of said arches is longitudinally tensioned between its points of attachment to said frame, whereby each of the spring

links thereof is flexed in an upwardly concave form to pretension said arch against downward deflection.

4. A spring deck as recited in claim 1 with the addition of means interconnecting each adjacent pair of said arches at spaced intervals along their lengths.

5. A spring deck as recited in claim 1 wherein said spring links are arranged in rows transverse to said arches, each of said rows including a single link in each of said arches, and wherein each of said rows of links constitutes 10 a single length of resilient wire, said wire being offset to form said links.

6. A spring deck as recited in claim 1 wherein said spring links are arranged in rows transverse to said arches, each of said rows including a single link in each of said 15 arches, and wherein each of said rows of links constitutes a single length of resilient wire, said wire being offset to form said links and affixed at its opposite ends to said frame.

7. A spring deck as recited in claim 1 wherein said 20 spring links are arranged in rows transverse to said arches, each of said rows including a single link in each of said arches, and wherein each of said rows of links constitutes a single length of resilient wire, said wire being formed to present a series of generally coplanar loops lying generally in the curved plane of said arches and connecting 25 portions joining said loops, each of said loops and the adjacent parts of the connecting portions constituting one of said links, each of said loops extending downwardly through the corresponding loops of a next adjoining wire, with the adjacent parts of said connecting 30 portions being disposed above the loop of said adjoining wire.

8. A spring deck as recited in claim 7 wherein the 35 loops in each of said wires are each full, closed loops, the portions of the wire at the closure of the loop overlapping each other slidably and extending in generally opposite directions from said loop, whereby longitudinal tension in said wire will tend to contract said loops.
